ADVERTISING SIGN HOLDER FOR VEHICLES

Filed Jan. 14, 1946

The drawing shows a cross-sectional view of a mechanical assembly. It consists of a base plate with a central vertical support. A horizontal rod is attached to the top of the support. A cylindrical component, labeled '10', is mounted on the rod. A spring, labeled '14', is wound around the rod between the base and the cylindrical component. The assembly is labeled 'Fig. 3.' in cursive text. Various dimensions are indicated: 18, 48, 10, 14, 44, 46, 12, 28, 30, 32, 20, 50, 14, 10, 34, 36, and II.

ADVERTISING SIGN HOLDER FOR VEHICLES

George J. Bruns, Kansas City, Mo., assignor to
Yellow Cab Company of Missouri, Kansas City,
Mo., a corporation of Missouri

Application January 14, 1946, Serial No. 641,023

1 Claim. (Cl. 40—125)

1

This invention relates to the art of display advertising and has for its primary aim to provide a holder for signs, which holder is constructed to permit quick and easy interchanging of the copy bearing sheet and to allow mounting the same in a suitable position where the sign is held in view.

One of the important objects of this invention is to provide an advertising sign holder for vehicles capable of being mounted on a part of the vehicle body and constructed to allow interchange of the sign panel without removal of the holder from its mounted position.

Further and very important objects of the invention are to provide an advertising sign holder capable of quick attachment to a vehicle body; having means for receiving and retaining an initially planar sign pane; having an unique frame that is sectional in character to allow comparatively inexpensive reconditioning of the holder in the event of damage thereto; and equipped with rugged adjustable anchoring elements for securing the entire sign assembly to the vehicle as a unit.

Other aims of the invention will appear during the course of the following specification referring to the accompanying drawing, wherein:

Fig. 1 is a front elevational view of an advertising sign holder for vehicles made in accordance with the present invention.

Fig. 2 is a longitudinal sectional view taken on line II—II of Fig. 1.

Fig. 3 is a fragmentary detailed sectional view on an enlarged scale taken on line III—III of Fig. 1; and

Fig. 4 is a fragmentary detailed sectional view taken on line IV—IV of Fig. 2.

In the form of the invention chosen for illustration the numeral 10 designates a backing member formed of sheet material that is laterally offset at its periphery to present a continuous flange 12 forming a cavity 14 within which the sign sheet 16 rests when such a sheet is in place for display. Flange 12 is angular in transverse cross section to provide a continuous shoulder 18 against which the edge of sign 16 will engage when the sign is confined within cavity 14.

Backing member 10 is strengthened by a plurality of embossed ribs 20 disposed substantially as shown in Fig. 1 for the purpose of permitting the attachment of the sign holder to a portion of the body 22 of the vehicle. These ribs 20 have a number of perforations 24 to receive anchor bolts 26 of a character clearly illustrated in Fig. 4. Bolts 26 have their heads 28 housed within

2

ribs 20 and the depth of these ribs is great enough to cause the upper surface of heads 28 to lie below the inner surface of backing member 10.

A series of nuts is threaded upon bolt 26 when assembly and mounting of the sign occurs. One nut 30 is drawn directly into contact with the outer surface of member 10 to maintain bolts 26 in place while the holder is manipulated for mounting upon vehicle 22. A second nut 32 is threaded onto each bolt 26 to form a shoulder against which the outer face of vehicle 22 is to rest and after the bolts 26 are threaded through holes 34 in the vehicle body 22, a final or third nut 36 is threaded onto the bolts 26 to rigidly secure the assembly in position.

Backing member 10 is further formed during the manufacture by cutting thereinto a U-shaped slit 38, the bight whereof extends across one end of member 10 along a line spaced inwardly from said end but parallel thereto. This bight portion of slit 38 is designated by the numeral 40 and the legs 42 of slit 38 extend along the two opposite longitudinal edges of member 10, as clearly shown in Fig. 1. This U-shaped slit 38 therefore, defines a tongue portion 44 in member 10 and it is this part of member 10 that is arched rearwardly to form a mouth 46 for the introduction of sign 16 into cavity 14. A retaining frame 48 is secured to flange 12 and this frame is L-shaped in transverse cross section. One leg of the L-shaped frame lies directly upon the outer surface of flange 12 while the other leg thereof embraces the member 10 and extends rearwardly toward the vehicle 22 when the sign assembly is mounted.

Frame 48 is sectional in character. The sections extend from a median line on the member 10 at the ends thereof around each corner to a median line on the longitudinal sides of member 10. Thus diagonally opposite sections of frame 48 are interchangeable and the frame may be reconstructed when damaged by removing the particular corner section in need of replacement. The sections of frame 48 have their ends in abutting relation at the centers of the ends and sides of member 10 and a small splicing member 50 overlaps a portion of each of the sections and is spot-welded thereto. These splicing members 50 may be pried from their normal positions if a part of frame 48 is to be replaced and after their removal that part of frame 48 between two of the said members 50 may be detached from the supporting flange 12 to which the frame is secured by rivets, bolts or any other suitable means. In the instance illustrated, the frame 48 is spot-

welded to flange 12. The frame and backing member 48 and 10 respectively, are longitudinally arched as clearly shown in Fig. 2, either to conform to the contour of that portion of the vehicle body 22 to which the frame is attached or to present a more pleasing appearance.

This arcuate formation is advantageous in that sign 16 is held under slight tension when it is in cavity 14. When the sign panel 16 is produced it is an initially flat piece of sheet material upon which is printed or otherwise placed, the advertising matter that is to be displayed to the observer.

The length of sign 16 is substantially the same as the distance between the end of cavity 14 opposite to mouth 46 and that part of slit 38 forming bight 40 thereof. Thus, when the sign is introduced into mouth 46 (see Fig. 2) and forced along cavity 14 below frame 48, the end first introduced will enter below frame 48 at the left end of the cavity (Fig. 2). When the end of sign 16 has reached this said end, the opposite end will move into cavity 14 whereupon the operator will slide sign 16 to the right (Fig. 2), to cause the entire marginal portion of sign 16 to underlie the frame 48 as it rests in cavity 14. Accidental displacement or escape of sign 16 from within cavity 14 is impossible due to the form of mouth 46 and the relative dimensioning of the parts as just above set down. When the sign holder is mounted its lower edge is equipped with drain openings 52 to insure that no water will collect within the lower part of cavity 14. A number of necessary drain openings 52 may be used to protect the material from which the sign holder is constructed and also to prevent rotting or staining of sign 16.

The conventional type of vehicle body 22 has some reinforcing therein and therefore, the location of anchor bolts 26 must be determined with respect to this reinforcing 54 as illustrated in Fig. 2. The angularity of ribs 20 and the employment of a number of perforations 24 give ade-

quate adjustment and attachment of the sign holder is thereby facilitated.

Having thus described the invention what I claim as new and desire to secure by Letters Patent is:

A holder for flexible normally flat advertising signs comprising an arcuate backing member for the sign, offset at its periphery to form a cavity at the normally front side thereof to receive the sign; an L-shaped frame secured to the periphery of the backing member and overhanging the marginal portion of the cavity to retain the sign within the latter; and a U-shaped slit formed in the backing member at one end thereof, with the bight of the U-shaped slit extending substantially entirely across the backing member, that portion of the member between the legs and bight of the U-shaped slit being arched rearwardly to form a mouth entering the cavity, the length of the sign being substantially the same as the distance between the bight of the slit and the edge of the cavity at the opposite end of the backing member, the distance between the innermost edges of the frame along the ends of the member being less than the length of the sign.
